UNITED STATES PATENT OFFICE.

FRANK T. WHEELER, OF SOUTHBURY, CONNECTICUT, ASSIGNOR TO
THE TRUMBULL ELECTRIC MANUFACTURING COMPANY, OF PLAIN-
VILLE, CONNECTICUT, A CORPORATION OF CONNECTICUT.

CUT-OUT.

No. 829,043.

Specification of Letters Patent.

Patented Aug. 21, 1906.

Application filed October 22, 1904. Serial No. 229,620.

To all whom it may concern:

Be it known that I, FRANK T. WHEELER, a citizen of the United States, and a resident of Southbury, in the county of Hartford and State of Connecticut, have invented a new and useful Improvement in Cut-Outs, of which the following is a specification.

The invention relates to cut-outs or "rosettes," as commonly called in the art, and more particularly to such a device arranged to be placed against a ceiling and form terminal contacts for incoming wires in such manner that said wires will be absolutely isolated one from the other to prevent short circuits.

The object of the invention is to provide a rosette having a base and cap detachably arranged with relation thereto and provided with means for insulating the incoming wires or leads.

A further object is to provide a rosette in which the base and cap must always be secured to one another in a well-defined and predetermined position.

A still further object is to provide a rosette having a base with recesses and abutments which will secure and seal the ends of the wire-carrying tubes commonly used to conduct electric wires to the rosette.

An especial feature and object of the invention is to provide a base and cap each having contacts arranged to interlock and with the parts provided with coöperating members which insure the contact of certain of the base-contacts with certain of the cap-contacts.

Referring to the drawings, Figure 1 is a top plan view of the base. Fig. 2 is a cross-sectional view through the base shown in Fig. 1. Fig. 3 is a bottom plan view of the base. Fig. 4 is a view in plan of the interior of the cap. Fig. 5 is a cross-sectional view through the cap appurtenant to the inserting-lug. Fig. 6 is a view in plan at the bottom of Fig. 5.

Heretofore it has been common practice to form rosettes or ceiling cut-outs in two parts with a pair of contacts on the base and a pair of coöperating contacts within the cap, said contacts arranged to interlock one with the other, and thus form the necessary conducting means from the wires entering the base to a pendent cord or other conducting means

attached to the contacts of the cap. In such devices it has in many instances been possible to secure the interlocking of the contacts of the base and cap by a partial revolution of the cap. In such devices, however, so far as known there has been nothing to prevent the interlocking of either of the base-contacts with either one of the cap-contacts. In such devices, of course, the positive and negative wires entering the base might be transposed with reference to the translator or apparatus receiving current from the cord or connection of the cap, inasmuch as the base-contacts are always relatively fixed as to polarity, and this polarity might be varied with reference to the translator receiving current from the cap-contacts by improper insertion and connection of the cap-contacts with reference to the base when rotating the cap to engage the contacts.

It is one of the objects of the present invention to preclude the possibility of such improper connection, and when the contacts of the cap are wired for positive and negative poles with reference to the positive and negative poles of the base the proper insertion of the cap is insured and the corresponding contacts of base and cap must always be inserted in a predetermined manner.

In the accompanying drawings the numeral 1 denotes the base, having in its upper surface depressions 2 3 of a sufficient diameter to receive the ends of wire-carrying tubes or conduits such as are commonly used in the electrical work. The recesses do not extend completely through the base, but have bottoms 4, each provided with an orifice 5 of sufficient diameter to permit passage of the wire borne in the conduit. On the inner surface of the base are provided contact members 6 7, each provided with angularly-disposed ends 8, depressed from the main contact portions 9 and secured to bosses 10 in such manner that the main contact portions 9 lie substantially in the same plane and parallel with the lower edge of the base.

Of course it is understood that the wires passing through the orifices 5 are secured to the angularly-disposed contact portions 8, as by binding-screws 11.

Intermediate the contacts 6 7 there is a bridge-piece 12, which starts from the inner edge of the base, as at 13, and extends across

the base and the depression 14 formed there-in. It does not, however, pass entirely across the depression 14, but terminates in the boss 10, as at 15, leaving a considerable space be-tween the end of the bridge and boss 10 and the inner wall of the depression 14. The cap (designated by 16) is also provided with contacts 17 18. The contact 18 is arranged to engage the contact 6, while the contact 17 10 engages the contact 7. These contacts are of ordinary and well-known form, upturned from the body of the cap and arranged to hook under and lock back of the contacts 6 and 7 upon partial rotation of the cap.

15 Projecting from the inner face of the cap is an inserting-lug 19 of approximately the proper size to drop between the end of the bridge at 15 and fill the space between said bridge and the inner wall of the depression 14 of the base and of such size that it will not drop between the side of the bridge, as at 20, and the adjacent edge of the contact 9. It will be seen from this arrangement that to insert the cap-contacts within the base and 25 turn said cap and contacts into locking position it is necessary that the projection 19 be inserted adjacent to the contact member 6 and on the clear side of said contact, so that the projection may be turned past the end 15 of the bridge 12. Thus it is impossible to insert the contact members of the cap except in predetermined relation to the base-contacts, and the contact member 18 must always be brought into engagement with the contact 6, 30 while the contact member 17 must always be brought into contact with the base-contact 7. For a clearer understanding the contacts of the cap and base are each marked "+" and "-" in order to show relative engagement of the 35 parts.

40 It is known to be old to form a base having openings through which the ends of conduit-tubes may project; but such devices have certain objections, inasmuch as the ends of the tubes are open and not sealed by an insulated material. In the form of device herein shown the recesses of the base-piece are simply depressions to receive the ends of the conduits and effectually close the rims or 45 ends of said tubes or conduits, permitting only the wire to pass through the base. This construction in sealed ceiling-work insures insulation between the incoming wires, conduits, and rosette without liability of short 50 circuits along the ceiling.

55 Obviously various changes might be made in the details of the several parts without departing from the spirit or intent of the invention, and, if desired, more than one insertion-60 lug may be used, and the lugs might be arranged in various manners so long as they insure a uniform and positive insertion of the cap-contacts with reference to the base-contacts in a predetermined manner.

What I claim as my invention, and desire 65 to secure by Letters Patent, is—

1. A rosette comprising a base and cap, contacts borne on said base and cap and ar-ranged to be interengaged and disengaged upon partial relative rotation of the parts, a 70 groove formed in the base and open adjacent to one of said contacts and closed appurtenant to the other of said contacts of the base, and a lug projecting from the cap and adapt-ed to enter and follow the groove, whereby 75 the contacts of the base and cap will interen-gage only in predetermined relation depend-ent upon the insertion of the lug of the cap within the groove of the base.

2. In a rosette in combination, a base, a 80 cap arranged to be secured thereto upon par-tial rotation, a groove formed in the base, contacts extending across said groove, a bridge extending across the groove adjacent to one of said base-contacts, cap-contacts 85 and a lug arranged upon the cap and adapted to enter the groove of the base, whereby the contacts of the cap and base may be engaged only in predetermined relation.

3. In combination in a rosette, a base pro-90 vided with contacts a bridge-piece extending between the contacts, a depression formed in the upper surface of the base appurtenant to each of said contacts and arranged to receive conduit-tubes, and apertures through the 95 bottom of said depressions connecting said conduit-tube depressions with the lower side of the base, said openings being arranged upon opposite sides of the bridge-piece.

4. In a rosette, in combination, a base of 100 insulating material, contacts secured to said base, a bridge of insulating material extend-ing partially across said base and interme-diate the contacts, said contacts having a portion extending along the side of the bridge, 105 and a second portion extending at an angle thereto as and for the purposes described.

5. In a rosette, in combination, a base of 110 insulating material provided with a depre-sion on its inner face, contacts arranged in said depression, a bridge of insulating ma-terial extending intermediate said contacts 115 terminating at one side in the wall of the depression and at its opposite end providing an opening between the bridge and inner wall of the depression a cap having a lug arranged to enter said opening whereby the contacts may be engaged in predetermined relation.

6. In combination in a rosette, a base of 120 insulating material, contacts mounted there-on, a bridge of insulating material extending between said contacts and terminating at one end at a distance from the wall of the base, a cap provided with contacts arranged to interlock with the base-contacts, and a lug 125 projecting from the said cap and arranged to be inserted in the recess of the base at the end of the bridge.

7. In a rosette comprising a base and cap, each bearing contacts arranged to interengage upon partial relative rotation of the base and cap, a groove formed in the base, a bridge-piece extending across the groove appurtenant to one of the base-contacts and a lug arranged upon the cap and adapted for insertion in the groove of the base, whereby the contacts of the cap and base may be engaged only in predetermined relation.

8. In combination in a rosette, a base having a central boss and annular groove extending thereabout, a bridge-piece extending

from the boss across the annular groove, contacts arranged on opposite sides of the bridge-piece, a cap provided with contacts arranged to project into annular groove to engage the base-contacts, and a lug arranged upon the cap purtenant to one of its contacts, whereby the cap and base contacts must be interengaged in predetermined relation.
